UNITED STATES PATENT OFFICE.

GEORGE W. WARDWELL, OF SOUTH NORWALK, CONNECTICUT, ASSIGNOR, BY MESNE ASSIGNMENTS, TO THE NORWALK IRON WORKS, A CORPORATION OF DELAWARE.

PLATE-VALVE.

1,359,006.

Specification of Letters Patent.

Patented Nov. 16, 1920.

Application filed January 24, 1920. Serial No. 353,878.

To all whom it may concern:

Be it known that I, GEORGE W. WARDWELL, citizen of the United States, residing at South Norwalk, in the county of Fairfield and State of Connecticut, have invented a new and useful Improvement in Plate-Valves, of which the following is a specification.

This invention relates to those valves that are particularly designed for use in connection with air compressors, although applicable to other types of pumping apparatus.

The object of the invention is to provide an efficient valve that can be cheaply manufactured, readily repaired, and easily assembled without alteration or substitution of parts for use either as an inlet valve or discharge valve as required.

The invention resides in a valve which has an annular seat plate and annular guard plate detachably secured together with a flat annular valve disk located between the seat and guard and normally held to the seat by a helical spring, the seat and guard being so shaped that when secured together the contour is such that they may be inserted into and held in the same opening in a compressor casing either side up, depending on whether the structure is to be used as an inlet valve or as a discharge valve.

In the accompanying drawings Figure 1 shows a central vertical section of a valve that embodies this invention set in a compressor casing for use as an inlet valve. Fig. 2 shows a similar view with the valve turned over, as when it is used for a discharge valve. Fig. 3 shows a plan of the annular seat. Fig. 4 shows a section of the seat on the plane indicated by the dotted line 4-4 on Fig. 3. Fig. 5 shows a plan of the guard. Fig. 6 shows a section of the guard on the plane indicated by the dotted line 6-6 on Fig. 5. Fig. 7 shows a plan of the valve plate. Fig. 8 is a section of the valve plate. Fig. 9 shows a side view of the valve complete.

The seat plate 1 is generally annular in form and has shoulders 2 and 3 around the edge facing in one direction and a shoulder 4 around the edge facing in the other direction, these shoulders providing a rim 5 on one face, a rim 6 on the other face and a flange 7 around the outside. In the center of this plate and supported by arms 8 is a seating hub 9.

The guard plate 10 is practically circular with a central opening 11 and an annular groove 12 in its inner face. The outer diameter of the main body of this guard plate is the same as the outer diameter of the rim 5 of the seat plate, and extending from the edge are legs 13, the outer walls of which are formed on arcs of a circle of a size that will closely fit into the recess in the seat plate that is surrounded by the rim 6. Pins 14 are inserted in holes made partly in the inner wall of the recess in the seat plate and partly in the outer edges of two of the legs of the guard plate for detachably securing the seat plate and guard plate together, which when assembled form a valve casing that is the same on both faces and is adapted to be inserted either way into the opening in the casing of the apparatus that is fitted to receive the valve.

In the space between the seat plate and guard plate the annular valve plate 15 is located, and normally pressing the valve plate against the seating face of the seat plate is a helical spring 16 which is retained in position by having one end resting in the annular groove 12 in the guard plate.

This valve may be located in the opening provided for it, for instance in an air compressor, in the inner wall 17 of the casing with the guard plate on the inside and the seat plate toward the inlet port 18, as in Fig. 1, if the device is to be employed as an inlet valve, or with the seat plate on the inside and the guard plate toward the discharge port 19, if the device is to be employed as a discharge valve. Thus located the device may be secured in place by any suitable means, as by a ported cage 20 placed upon it, the cage being shaped to fit against either the shoulder 3 or the shoulder 4 depending on whether the device is to be used as an inlet valve or as a discharge valve, and a cap 21 that is screwed into the outer wall 22 of the casing against the cage so as to force the valve seat tightly into its pocket.

When the valve plate is drawn from the seat by suction as in inlet work, or forced from the seat as in discharge work, the air or other fluid being pumped passes through the central opening in the valve plate also around the edge of the valve plate between the legs of the guard plate. By unscrewing the cap the cage and valve may be readily removed through the opening into which

the cap is screwed, and when the valve is taken out the pins which hold the parts together may be pushed out and the valve sections readily separated for cleaning, repairs or renewal of any parts. There are but few parts to this valve and all are cheap to manufacture and easy to assemble. The guard plate acts as a protector, guide and container for the spring and the valve plate which is merely a flat piece of steel that fits closely against the flat seating surface of the seat plate.

The invention claimed is:—

1. The combination with the wall of a compressor cylinder having an opening therethrough, of a valve comprising two casting plates, one fitting within the other and secured thereto, said plates when fitted together forming a casing having both faces about its periphery shaped to closely conform to said opening, whereby the valve may be tightly fitted therein with either face outward, one plate having a central port and the other plate having a closed center with encircling ports, a flat valve disk with a central port located between the plates, and a spring normally holding the valve disk against the plate having the closed center.
2. A compressor intake and discharge valve comprising a circular seat plate with annularly arranged ports and a flanged edge, a circular guard plate with a central port and flanged edge fitted into the flanged edge of the seat plate, said plates when fitted together presenting substantially the same conformation on both faces about the periphery, a flat ported valve disk located in the space between the plates, and a spring normally thrusting the valve disk against the seat plate.
3. The combination with the wall of a

cylinder having an opening therethrough, of a valve having both faces about its periphery shaped to closely conform to said opening, whereby the valve may be located therein with either face outward, said valve comprising a recessed seat plate, a guard plate fitted in the recess in the seat plate, a flat valve disk located between the seat plate and guard plate, a spring thrusting between the guard plate and the valve disk, a ported cage engaging the seat plate for retaining the valve in place, and a plug securing said cage in place.

4. A valve comprising a seat plate, a guard plate fitted to the seat plate and having legs spacing it therefrom, pins detachably fastening the seat plate and guard plate together, a valve disk located between the seat plate and guard plate, and a spring thrusting the valve disk against the seat plate.

5. A compressor intake and discharge valve comprising an annular seat plate with a solid center and ports about the center, a guard plate with a port through its center fitted into said seat plate, said plates when fitted together presenting substantially the same conformation on both faces about the periphery, whereby the valve will closely fit the same opening either side out, a flat valve plate with a central port located between the seat plate and guard plate, and a spring thrusting between the guard plate and valve plate.

6. A valve comprising a seat plate having a closed center and openings about the center, a guard plate having a central perforation fitted to the seat plate, a flat disk located between the plates, and a spring thrusting the disk against the seat plate.

GEORGE W. WARDWELL.
